MILKING MACHINE PULSATORT

Sam P. Wall, Chicago, Ill., assignor to Rite-Way
Products Co., Chicago, Ill., a corporation of
Delaware

Application January 17, 1947, Serial No. 722,663

14 Claims. (Cl. 137—145.3)

1

This invention relates to vacuum type milking machine pulsators.

Pulsators of the type with which the present invention is primarily concerned consist of a reciprocating pulsation valve which applies vacuum and atmospheric pressure alternately to a pulsation line. The pulsation valve moves rapidly, with a pause between reversals. The duration of the pause is determined by a timing or control valve. Separate piston and cylinder combinations are controlled by and in turn operate the respective valves.

It is one of the objects of the present invention to provide a pulsator of the above mentioned type wherein the pistons are self-aligning. It is another object of the present invention to provide a structure wherein the valve and the cylinder for actuating the same are a unitary structure which slide over the body of the pulsator. This reduces the number of parts and facilitates assembly of the pulsator not only in the manufacture of the same but also by the user who must occasionally disassemble it for cleaning purposes. This also simplifies the drilling of the air passageways in the manufacture of the pulsator. It is a further object of the present invention to provide a pulsator structure wherein the air passageways through the stationary part of the pulsator are formed in a single forging or block. This simplifies the operations of forming the vacuum passageways or ports and simplifies the problem of reducing air leakage.

The attainment of the above and further objects of the present invention will be apparent from the following specification taken in conjunction with the accompanying drawings forming a part thereof.

In the drawings:

Figure 1 is a top view of the pulsator of the present invention with the cover thereof removed and with one of the cylinders shown in section;

Figure 2 is a section taken along the line II—II of Figure 1, with the pulsation valve shown in elevation;

Figure 3 is a view of the left side of Figure 1 with parts of the cover broken away and the control valve shown in longitudinal section;

Figure 4 is a plan view of the pulsator body;

Figure 5 is a sectional view taken along the broken line V—V of Figure 4 and looking in the direction of the arrows;

Figure 6 is a bottom view of the pulsation valve;

Figure 7 is a transverse sectional view of the pulsation valve taken along the line VII—VII of Figure 1 and looking in the direction of the arrows;

2

Figure 8 is a sectional view taken along the line VIII—VIII of Figure 7 and looking in the direction of the arrows;

Figure 9 is a fragmentary sectional view taken along the line IX—IX of Figure 6;

Figure 10 is a bottom view of the control valve; and

Figure 11 is a sectional view taken along the line XI—XI of Figure 10.

Reference may now be had more particularly to the drawings wherein like reference numerals designate like parts throughout.

The pulsator of the present invention comprises a pulsator block or body 1 which is a brass forging and has a lower neck portion 2 forming a hollow chamber 3, and has an upper cylindrical portion 4 that has a circular top surface 5 that is ground and lapped to be perfectly flat. A vacuum line receiving nipple 7 is an integral part of the casting and has a central bore 8 therethrough which opens into the chamber 3. The nipple 7 is adapted to receive a rubber hose or the like that is connected to a source of vacuum. The body 1 has on one side thereof two horizontally extending holes 10 and 11 in which are secured nipples 12 and 13 each for receiving a flexible hose which extends to suitable nipples on a milking machine claw in a manner known in the art. The holes 10 and 11 are intersected by port holes 14 and 15 that are drilled in the body 1 from the top surface thereof. Between the holes 14 and the holes 15 there are formed a pair of holes or ports 16 which extend downwardly from the surface 5 to and intersect an inclined bore 18 that connects the ports 16 with the chamber 3.

A series of parallel air passages 21, 22, 23 and 24 are drilled from one side of the body 1 in the upper cylindrical portion thereof. The outer end of each of the four passages is permanently closed by a plug 25, each plug consisting of a short length of wire that makes a snug fit in the passageway and is soldered or otherwise permanently sealed therein with the outer face of the wire 45 terminating flush with the cylindrical surface 4.

Two ports 27 and 28 are drilled from the top surface 5 to intersect the passage 21. Two other ports 29 and 30 are drilled from the surface 5 to intersect the passageway 22. Two other ports 31 and 32 extend from the surface 5 to and intersect the passageway 23 and two additional ports 33 and 34 are drilled from the surface 5 to and intersecting the passageway 24. It is thus apparent that the passageway 21 connects the ports 27 and 28, the passageway 22 connects the ports 29—30, the passageway 23 connects the ports

31—32, and the passageway 24 connects the ports 33—34.

A vacuum port or passageway 36 extends from the surface 5 to the chamber 3, as may be seen from Figures 2 and 4. In addition to the above the pulsator body has a vacuum control port 39 that extends downwardly from the surface 5 to and intersects a downwardly sloping passageway 40 which is in alignment with and opens into a bore 41 which is internally threaded as at 42. An inclined bore 43 connects the bore 41 with the vacuum chamber 3, as may be seen from Figure 5. The bore 43 is at such an angle that a drill following along the center line 44 of the bore 43 can be used, which drill enters the bore 41. As a result the passageway 43 may readily be cleaned as by passing a wire therethrough from the outside of the base through the open end of the bore 41. The bore 41 is closed by a manually adjustable speed regulating screw 45 that has a knurled adjusting head 46 and may be locked in position by a lock nut 47. A plurality of concentric grooves 48 are formed in the body 1 surrounding the bore 41. A washer 49 of leather or the like, is compressed into the grooves 48 by the lock nut 47 and acts to tension the lock nut and thereby facilitates retaining of the regulating screw 45 in the position in which it is adjusted.

Four mounting posts 55 are mounted on the top of the pulsator body, as by threading the posts into tapped openings 56 in the top of the pulsator body. These posts are adapted to receive and hold pistons that extend into cylinders, to be presently more fully described.

A pulsation valve 69 and a timing or control valve 61 are positioned on the flat surface 5. Each of the valves has a flat bottom surface adapted to slide along the surface 5. The pulsation valve 60 has, on the under side thereof, a rectangular recess 63 which is adapted to overlaid the vacuum passageways 16 and connect them alternately with the ports 14 and with the ports 15, depending upon the position of the pulsation valve. The pulsation valve 60 also has a pair of similar slots 64—65 on opposite sides of the recess 63 each of which slots is open at the base of the pulsation valve and at the side thereof. In addition the under surface of the pulsation valve 60 has an elongated recess 66 extending across the transverse center line of the valve and a pair of separate shorter recesses 67—68. Above the recesses and slots 63 through 68 the pulsation valve has two similar cylinder bores 70 and 71 formed therein separated by a wall 72 which maintains the cylinder bores separate from one another. A port 73 is drilled from the under side of the pulsation valve at the recess 67 and connects the recess with the interior of the cylinder 71 adjacent the dividing wall 72. A similar port or passageway 74 connects the recess 68 with the interior of the cylinder 70.

The control valve 61 has a flat bottom surface in which are formed, respectively, a rectangular recess 77 which opens to the atmosphere at one side of the control valve, and a U-shaped recess 78 having arms 79—79, and a pair of rectangular recesses 80—81. Above the base of the control valve the valve is provided with two cylinders 82—83 separated by a wall 84. A port or passageway 85 extends from the recess 80 into the cylinder 82 adjacent the wall 84 and a similar port or passageway 86 extends from the recess 81 into the cylinder 83 adjacent the partition wall 84.

A pair of similar pistons 90—90 extend into the respective bores 82—83. Each piston comprises

a body 91 undercut at its forward end to receive a cup-shaped gland 92, of leather or the like, which is held in place by a screw 93 and a washer 94. A circular peripheral flange 96 on the piston limits the extent of insertion of the piston into the cylinder bore. On its rearward side the piston has a circular protuberance 93 which has a hole 94 therethrough to permit sliding of the piston onto one of the posts 55. The two pistons are assembled within the cylinder bores 82—83 and then the assembly is slipped over a pair of posts 55, the posts passing through the openings 94 in the pistons. This fixes the positions of the pistons and permits sliding movement of the control valve between the two posts 55. The pulsation valve likewise has two pistons 90 similarly assembled therein and held each on one of the other two posts 55.

An explanation will now be given of the manner of operation of the mechanism thus far described. Assume that the parts are in the positions illustrated and that vacuum is applied to the nipple 7 and thence to the chamber 3. The vacuum connection extends by way of the holes or passageways 16, thence by way of the recess 63 in the pulsation valve to the passageways 14 and the nipple 12, thus applying vacuum to the nipple 12. At this time the passageways 15 are overlaid by the recess 64 which, being open to atmosphere, applies atmospheric pressure to the nipple 13. At the same time vacuum is applied from the chamber 3 by way of the bore 43 (Fig. 5), thence through the space between the threads of the regulating screw 45 and the threads of the bore 41, thence by way of the passageway 40 to the vacuum port 39 which is thus always connected to vacuum by way of the long spiral passageway between some of the threads of the regulating screw and the threads of the bore 41. The port 39 is overlaid by the recess 66 which at this time extends to the port 33. Vacuum is thus extended to the port 33 and thence through the passageway 24 to the port 34. The port 34 is overlaid by the passageway 80 which, through the port 85, communicates with the interior of the cylinder 83. Vacuum is thus applied to the interior of the cylinder 83 thereby drawing the air out of that cylinder. At the same time the port 27 is under the slot 64 of the pulsation valve so that atmospheric pressure is applied through the slot 64, port 27, passageway 21 and the port 28, which is overlaid by the recess 81 that connects with the cylinder 82 through the passageway 86 in the control valve. Atmospheric pressure is thus applied to the cylinder 82. Since there is atmospheric pressure on one side of the dividing wall 84 and vacuum on the other side thereof the control valve 61 commences to move in a direction downwardly as seen in Figure 1, to its alternate position. The rate of its movement is determined by the rate of air flow through the restricted passageway set by the regulating screw 45.

When the control valve has traveled to its alternate position abutting the flange 96 of the piston it establishes vacuum connections for operating the pulsation valve to its alternate position. These connections are as follows: Vacuum is applied from the passageway 36 and recess 78 to one of the arms 79 thereof which is now over the port 30. This establishes vacuum connection from the port 36 by way of the passageway 78 to the port 30, thence by way of the passageway 22 to the port 29 which is overlaid by the recess 67 of the pulsation valve. The recess 67 com-

municates the vacuum connection to the cylinder 71 by way of the passageway 73. At the same time the atmosphere recess 71 of the control valve 61 is over the port 32, thus connecting atmospheric pressure via that port and passageway 23 to the port 31, which port 31 is overlaid by the recess 68 in the pulsation valve, which, through the port 74, connects atmospheric pressure to the cylinder 70 of the pulsation valve. The cylinders of the pulsation valve thus have atmospheric pressure on the lower side of the wall 72 and vacuum on the opposite side thereof, as seen in Figure 1. The pulsation valve now moves in a direction upwardly, as seen in Figure 1, to its alternate position. It moves to that position rapidly because the vacuum and atmospheric connections to the cylinders of the pulsation valve entirely by-pass the restricting screw bore 41. In its alternate position the recess 63 of the pulsation valve connects the vacuum ports 16 with the ports 15 thus applying vacuum to the nipple 13. The atmospheric slot 65 of the pulsation valve now overlies the ports 14 and the port 33 thus applying atmospheric pressure to the nipple 12 and applying atmospheric pressure to the port 33, thence through the passage 24 to the port 34 which is overlaid by the slot 80 of the control valve 61. At this time the recess 66 connects the vacuum port 39 with the port 27 thus applying vacuum through the port 27 and passageway 21 to the port 28 which is overlaid by the recess 81 of the control valve, which recess 81 is connected to the cylinder 82 by passage 86. The control valve thus immediately commences to return to the position illustrated in Figure 1 and, when it returns to that position, it establishes connections for immediately returning the pulsation valve to the position illustrated in Figure 1. It is thus apparent that by this arrangement when the pulsation valve reaches an extreme position it establishes vacuum and atmospheric connections for moving the control or timing valve from the position in which it is to its alternate position and that the control valve moves at a speed determined by the setting of the screw 45. When the control valve reaches its alternate position it then establishes vacuum connections for moving the pulsation valve to a position other than in which it is.

The pulsation valve and the control valve thus reciprocate between the posts 55—55 alternately. Grooves 100—101 are milled across the flat surface 5 of the pulsator body in such a position that the bottoms of the movable valves 60—61 just reach the grooves 100 or 101 in the alternate positions of the valves. This facilitates the maintenance of flat surfaces at the areas of rubbing of the valves on the surface 5 notwithstanding wear that may take place.

The pistons for each pair of cylinders are self-aligning because each piston is free to turn about the vertical axis of its mounting post 55. If there is any wear on the rubbing surfaces constituting the bottoms of the valves and the corresponding parts of the top 5 on which the valves slide this wear does not affect the seating of the valves because the pistons are free to slide downwardly on the mounting posts and thus permit the valves to be self-seating on the surface 5. Each valve, with its cylinder bores formed therein and with its associated pistons constitutes a pneumatic mechanism which may easily be removed from the pulsator block 1 by simply lifting the same along the posts 55, and may be replaced equally

easily. This facilitates inspection and repair of the mechanism.

The pneumatic mechanisms are enclosed within a dome-shaped cover 110 the top of which has a circular opening 111, the surrounding metal of the cover being flared downwardly and at an angle, as indicated at 112. A porous metal filter disk 113 rests on the seat 112 and is held in place by a cap 114 that has fingers 115 bearing against the filter disk 113 and spacing the cap 114 therefrom to allow atmospheric air into the space between the cap and the filter disk. The shank of a screw 116 is welded to the under side of the cap 114 and makes a snug sliding fit through the filter 113 and at its bottom is threaded into a tapped hole 117 at the top of the pulsator body.

In compliance with the requirements of the patent statutes I have here shown and described a preferred embodiment of my invention. It is, however, to be understood that the invention is not limited to the precise construction here shown, the same being merely illustrative of the principles of the invention.

What I consider new and desire to secure by Letters Patent is.

1. A milking machine pulsator comprising a pulsator block, a hose-receiving nipple extending therefrom, and means for applying vacuum and atmospheric pressure to said nipple alternately in cycles, said means including a valve reciprocable on the block and controlling the application of vacuum and atmospheric pressure to said nipple, and pneumatic means for operating the valve comprising a pair of pneumatic cylinders formed in the valve, pistons in said cylinders, and means for holding the pistons with respect to the block against movement in the direction of the longitudinal axes of the cylinders.

2. A pulsator comprising a block having a flat top and having air passageways therein terminating in ports at the top, a pair of separate valves slideable on the top of the block and having passageways at their lower surface for interconnecting different ones of the ports, and means for moving the valves comprising cylinder bores formed in the respective valves, and pistons pivoted on the block and extending into the cylinder bores.

3. A pulsator comprising a block, air passageways in said block and terminating in ports at the top thereof, a valve slideable on said block over said ports, said valve having a pair of aligned cylinder bores opening on opposite faces thereof, pistons in said bores, said pistons including portions extending outside of said cylinder bores, means pivotally connecting said outside extending portions of the pistons to said block for holding the pistons in position on the block while permitting aligning movement thereof, said cylinder bores being movable with respect to the pistons to move the valve over different ports of the block.

4. A pulsator comprising a block, air passageways in said block and terminating in ports on the outside thereof, a valve slideable on said block over said ports, said valve having a pair of aligned cylinder bores opening on opposite faces thereof, pistons in said bores, said pistons including portions extending outside of said cylinder bores, posts on which the outside extending portions are slideable, said posts being mounted on the block and extending at right angles to the longitudinal axes of the bores and holding the pistons in position on the block, said cylinder bores being

movable with respect to the pistons to move the valve over different ports of the block.

5. A milking machine pulsator comprising a pulsator block having a ported surface, a pneumatically operated mechanism including a valve resting and slideable on said surface, said mechanism being freely movable away from said surface and including a pair of pneumatic cylinders and a pair of pistons one for each cylinder, one of said pairs comprising one integral unit and the other pair comprising separate units, the valve being an integral part of the said integral unit and supporting the rest of the pneumatically operated mechanism on said block, and guide means for guiding the respective separate units in movements angularly disposed with reference to the direction of sliding movement of the valve on the surface.

6. A milking machine pulsator comprising a pulsator block having a ported surface, a pneumatically operated mechanism including a valve resting and slideable on said surface, said mechanism being freely movable away from said surface and including a pair of pneumatic cylinders and a pair of pistons one for each cylinder, one of said pairs comprising one integral unit and the other pair comprising separate units supported by said integral unit, the valve being an integral part of the said integral unit and supporting the pneumatically operated mechanism on said block, and means for positioning the respective separate units on the block, said positioning means comprising swivels about which the separate units are free to turn.

7. A milking machine pulsator comprising a pulsator block having a ported surface, a pneumatically operated mechanism including a valve resting and slideable on said surface, said mechanism being freely movable away from said surface and including a pair of pneumatic cylinders and a pair of pistons one for each cylinder, one of said pairs comprising one integral unit and the other pair comprising separate units supported by said integral unit, the valve being an integral part of the said integral unit and supporting the pneumatically operated mechanism on said block, and means for positioning the respective separate units on the block, said positioning means comprising posts mounted on the block at right angles to the longitudinal axes of the cylinder bores, and the said separate units being slideable on the posts.

8. A pulsator comprising a block having air passageways therein terminating in ports on the outside of the block, a pair of valves separately slideable on the block over the ports and having passageways for interconnecting different ones of the ports, cylinder bores formed in the respective valves, pistons in the respective bores and extending outside of the bores, posts extending at right angles to the longitudinal axes of the cylinder bores and pivotally mounting said pistons on said block but permitting a free movement of the pistons and with them the cylinders and the valves in a direction towards and from the block at right angles to the longitudinal axes of the cylinder bores whereby the valves are self seating on the block, said posts holding the pistons against movement on the block in a direction parallel to the longitudinal axes of the cylinder bores.

9. A milking machine pulsator comprising a pulsator block having a ported surface, a pair of parallel posts on said block, a pneumatic mechanism between said posts having two separate

members slideable on said posts and having a reciprocable member reciprocating between said separate members and together with said members constituting a pair of cylinders and pistons, said pneumatic mechanism being slideable onto and off of said posts, said pneumatic mechanism including a valve resting on said ported surface and reciprocated thereon by said reciprocable member and supporting the pneumatic mechanism.

10. A milking machine pulsator comprising a pulsator block, a pulsation valve and a timing valve reciprocable thereon, and pneumatic means for operating the valves, said means comprising pneumatic cylinders formed in the respective valves, pistons in said cylinders, and means on the block for holding the pistons against movement directly towards and directly from one another.

11. A milking machine pulsator having pneumatically operated mechanism comprising a pair of cylinders and a pair of pistons one for each cylinder, one of said pairs constituting one integral unit and the other pair comprising separate units, swivel means positioning the separate units and permitting their relative turning about spaced parallel axes to bring them into alignment with one another, said integral unit being reciprocable with respect to the separate units, and said reciprocating unit being provided with a valve surface and valve ports.

12. A milking machine pulsator valve comprising a valve member having a smooth sliding bottom surface, ports formed in said valve member, said ports comprising grooves in said surface, said valve member having two cylinder bores opening on opposite sides thereof and in alignment with one another and with their longitudinal axes parallel to said bottom surface, and a wall constituting a part of the valve member and separating the bores.

13. A milking machine pulsator comprising a pulsator block, a pulsation valve and a timing valve both reciprocable on the block, four separate parallel bores in said block, a closure for the outer end of each bore, the block having ports thereon controlled by the pulsation valve and passageways from the ports communicating with the respective bores and the block also having ports thereon controlled by the timing valve and also passageways from the last mentioned ports communicating with the respective bores, and pneumatic means controlled by movement of air through said passageways and ports and valves for operating said valves, said pneumatic means including cylinder elements and cooperating piston elements above the block.

14. A milking machine pulsator comprising a pulsator block, a pulsation valve and a timing valve both reciprocable on the block, four separate parallel bores in said block, a closure for the outer end of each bore, the block having ports thereon controlled by the pulsation valve and passageways from the ports communicating with the respective bores, the block also having ports thereon controlled by the timing valve and also passageways from the last mentioned ports communicating with the respective bores, and pneumatic means controlled by movement of air through said passageways and ports and valves for operating said valves, said block having an open bottom cavity in the lower surface thereof, an air passageway extending through the block from the cavity and opening at the top surface of the block in the path of movement of one of

9

said valves and constituting a port leading there-to, and means for extending vacuum connections to said cavity.
